Des. 227,626
Patented July 10, 1973

227,626

BABY'S CRIB OR THE LIKE

Scott M. Ferguson, 8870 Root St., Apt. 1,
Niles, Ill. 60648

Filed Sept. 15, 1971, Ser. No. 180,943

Term of patent 14 years

Int. Cl. D6—01

U.S. Cl. D6—16

FIG.1

FIG.2

FIG.4

FIG. 1 is an isometric view of a baby's crib or the like showing my new design with the entrance portion in open condition;

FIG. 2 is a front elevational view;

FIG. 3 is a top plan view; and

FIG. 4 is a bottom plan view thereof.

I claim:

The ornamental design for a baby's crib or the like, as shown and described.
